Primary Examiner—Marcus A. Jackson(74) *Attorney, Agent, or Firm*—Brinks Hofer Gilson & Lione(57) **CLAIM**

We claim the ornamental design for a fluorescent lamp, as shown and described.

DESCRIPTION

FIG. 1 is a top view of a fluorescent lamp of the present invention;

FIG. 2 is a front view thereof;

FIG. 3 is a first side view thereof;

FIG. 4 is a second side view thereof;

FIG. 5 is a rear view thereof; and,

FIG. 6 is a bottom view thereof.

The appearance of the top half portion of the shell is optically transparent.
